UNITED STATES PATENT OFFICE.

CARL C. CHITTIM, OF TULSA, OKLAHOMA.

COMBINED ADJUSTABLE CHAIR AND COT.

1,306,102.

Specification of Letters Patent. Patented June 10, 1919.

Application filed March 6, 1919. Serial No. 281,045.

To all whom it may concern:

Be it known that I, CARL C. CHITTIM, a citizen of the United States, residing at Tulsa, in the county of Tulsa and State of Oklahoma, have invented certain new and useful Improvements in Combined Adjustable Chairs and Cots, of which the following is a specification.

The invention relates to an article which is readily convertible from a chair to a cot and which is adjustable in either adaptation to the convenience and needs of the user and which when not required for immediate use may be reduced to a compact bundle for convenience and storage and handling thereby adapting the device for tourists and out door requirements.

The drawings illustrate a preferred embodiment of the invention. However, it is to be understood that in adapting the same to meet different conditions, various changes in the form, proportion, and minor details of construction may be resorted to without departing from the nature of the invention as claimed hereinafter.

The drawings illustrate the preferred form of the invention and various adaptations thereof, and in the same,

Figure 1 is an elevation illustrating the device as adapted for a chair, the dotted lines showing an adjusted position thereof.

Fig. 2 is a front view, the parts appearing in the relation shown in Fig. 1.

Fig. 3 is a section on the line 3—3 of Fig. 2 looking to the left as indicated by the arrow.

Fig. 4 is a section on the line 4—4 of Fig. 3 looking to the right as designated by the arrow.

Fig. 5 is an elevation showing the device adapted for use as a cot, the dotted lines indicating an adjustment of the head section.

Fig. 6 is a view similar to Fig. 5 with the leg sections folded.

Fig. 7 is a view showing the parts folded longitudinally, the covering being omitted.

Fig. 8 is a view showing the device reduced to a compact bundle for convenience of handling and storing.

Fig. 9 is a detail view showing the connecting means between an end section, the leg section coöperating therewith and the transverse connecting piece.

Fig. 10 is a sectional detail on the line 10—10 of Fig. 9 looking in the direction of the arrow.

Fig. 11 is a sectional detail on the line 11—11 of Fig. 3 looking downward as indicated by the arrow.

Fig. 12 is a sectional detail showing the connecting means between an end section and the coöperating leg section.

Corresponding and like parts are referred to in the following description and indicated in the several views of the drawings by like reference characters.

The device comprises a plurality of similarly formed main sections A, B and C which are pivotally connected to admit of various relative adjustments necessary in converting the article from one use to another and in adapting the same to the convenience of the user in either one of its adaptations. Similarly formed sections D, E and F are pivotally connected to the main sections by means shown most clearly in Fig. 12 whereby these sections may be collapsed and adjusted. The sections E and F constitute legs for supporting the device in horizontal position, as indicated in Fig. 5. The section D is essentially a brace and co-operates with leg sections G and H which are pivotally connected to each other, the section G being pivotally connected to the section A and the section H being detachably connected to the said section A. In either adaptation of the device the leg sections G and H are held in the required adjusted position by means of the brace section D and the adjustable pivot connection between the sections G and H.

Each of the main sections comprises side bars which are pivotally connected by means of plates 1, two being provided at each joint and disposed upon opposite sides of the bars of adjacent sections to which they are pivotally connected. Each of the plates 1 is formed with a transverse slot 2 which receives a pin 3 projecting laterally from one of the bars whereby provision is had for a limited relative movement between the sections to allow for various adjustments in the conversion of the device from one adaptation to the other and in the adjustment of the same in either adaptation. The main sections are of different relative lengths and

the section A constitutes the bottom of the chair, as indicated in Figs. 1 and 3 and forms the head section of the cot, as shown in Fig. 5. In either adaptation the inclination of the main section A may be varied to suit the convenience of the occupant. The intermediate section B constitutes the back of the chair, as shown most clearly in Figs. 1 and 3 and the section C forms the foot section of the cot. A covering 4 is applied to the sections and may consist of canvas, duck or other textile, said covering being secured at its edges to the side bars of the respective sections and having edge portions cutaway so as to clear the joints. One end of the covering 4 is provided with a hem or tuck 5 to receive a cross piece 6, Fig. 2. The cross piece 6 constitutes the front of the chair bottom, and the head rest of the cot and serves to bracingly connect the outer ends of the side bars comprising the leg section H. For this purpose the ends of the cross piece 6 are provided with headed studs 7 which engage slotted plates 8 secured to the inner faces of the side bars comprising the leg section H. This is shown most clearly in Fig. 9.

The sections D, E and F are of similar formation, each consisting of crossing bars pivotally connected at the point of crossing to admit of the sections folding one against the other, as shown most clearly in Fig. 7. The bars are offset at their point of crossing so that when folded they may lie one against the other. While these sections may be constructed in any manner it is preferred to construct them of wooden bars which are connected by metal straps 9 which admits of the bars lying in the same plane so as to fold closely one against the other. Each of the leg sections E and F is provided with a brace 10 which is pivoted at one end to one of the bars and is adapted to have its opposite end detachably engage the companion bar, thereby holding the bars in a given position when the leg sections are extended for use. The leg sections may be held in upright position by means of a brace 11 which is preferably pivoted at one end to a main section and is adapted to have its opposite end detachably engage the leg section. Fig. 5. The brace section D is provided at its lower end with headed studs 12—Fig. 7—which are adapted to engage slotted plates 13 secured to the inner faces of the bars and comprising the leg section H. Figs. 3 and 11. A pivoted latch 14 engages the studs 12 and retains them in the slots of the plates 13. Each of the bars comprising the sections D, E and F is hinged to the respective main sections in the manner shown most clearly in Fig. 12, an ordinary hinge 14 being provided and having its

leaves secured to the respective bars or members of the several sections.

65

The bars of the leg section G are connected to the inner ends of the bars of the main section A by curved plates 16 which are rigidly secured to the bars G and pivotally connected to the bar A. Each of the bars G is provided upon its inner side near its upper end with a headed stud 18 which is adapted to operate in the slot 19 of a longitudinally slotted plate 20 secured to the outer side of each bar or member of the leg section H. A toothed bar 21 pivoted at its upper end to the bar H is adapted to engage the headed stud 18 and hold the latter in the required adjusted position. The toothed bar 21 performs the office of a latch and is retained in operative position by means of a keeper 22 which is pivotally mounted on the bar H near the lower end of the plate 20. Each of the bars H is provided upon the outer side near its upper end with a slotted plate 23 which is adapted to engage a headed stud 24 upon the inner side of the outer end of each bar of the section A. Fig. 9. A pivoted latch 25 cooperates with the stud 24 to retain it in the slot of the plate 23. Straps 26 form adjustable connecting means between remote ends of the sections A and B, thereby admitting of the inclination of the section B being adjusted, as indicated most clearly by the dotted lines in Fig. 1. Hook members 27 serve to secure the section C when the device is adjusted for use as a chair. Fig. 1.

120

From the foregoing taken in connection with the accompanying drawings it will be understood that the invention provides an article which may be reduced to a compact bundle to be conveniently carried in an automobile or other vehicle for out door use or which may be stored so as to occupy a minimum amount of space and also to admit of convenience in handling. When required for use the device may be quickly set up to be used either as a chair or as a cot. When used as a chair the section B may be variously inclined, as indicated in Fig. 1 to suit the comfort and requirements of the occupant and the inclination of the section A may likewise be varied, the various adjustments being readily effected and the parts made secure against displacement in any adjusted position. When the device is required for use as a cot it may be arranged, as indicated in Fig. 5 and the inclination of the section A may be changed to elevate the head of the occupant so as to secure ease and comfort.

The foregoing description and the drawings have reference to what may be considered the preferred, or approved form of my invention. It is to be understood that

I may make such changes in construction and arrangement and combination of parts, materials, dimensions, et cetera, as may prove expedient and fall within the scope 5 of the appended claims.

Having thus fully described my invention, what I claim as new and desire to secure by Letters Patent is:—

1. An article substantially as herein specified, comprising a plurality of similarly formed main sections and a plate connecting adjacent sections and transversely slotted intermediate of its ends and having one end pivoted to an end of one of the sections and having its other end pivoted to the other section a distance from the end thereof, and fastening means connecting the end of the last mentioned section to the intermediate slotted portion of the plate.
2. In an article of the character set forth, side members, bars having pivotal connection with opposite end portions of the side members, said bars crossing an adjustable pivot connection between the bars at their point of crossing and means for securing the pivot connection in relative adjusted position.
3. In an article of the character set forth, side members, bars having pivotal connection with opposite end portions of the side members, a longitudinally slotted plate on one of the bars, a pivot stud on the other

bar coacting with the slotted plate and a toothed latch for securing the pivot stud in adjusted position.

35

4. In an article of the character specified, collapsible side members, supporting means therefor including pivotally connected crossing bars, pivoted brace bars hingedly connected at one end to the collapsible members, 40 slotted plates and studs detachably connecting the brace bars at the opposite end to the supporting means and latch elements retaining the studs and plates in adjusted position.

5. In an article of the character set forth, collapsible side members, a leg section pivoted at one end to the collapsible side members, a second leg section detachably connected to the opposite ends of the side members and having adjustable pivotal connection with the first mentioned leg section, a cross piece detachably connecting the ends of the members comprising a second leg section, and a brace section having pivotal connection with the side members and detachable connection with the members of the second leg section.
